(57) **CLAIM**

The ornamental design for a washer, as shown and described.

DESCRIPTION

FIG. 1 is a perspective view of a first presently preferred embodiment of the washer of my new design from the top; FIG. 2 is a perspective view thereof from the bottom; FIG. 3 is an elevational view thereof from the front; FIG. 4 is an elevational view thereof from the rear;

FIG. 5 is an elevational view thereof from the left; FIG. 6 is an elevational view thereof from the right; FIG. 7 is a top plan view thereof; FIG. 8 is a bottom plan view thereof; FIG. 9 is a perspective view of a second presently preferred embodiment of the washer of my new design from the top; FIG. 10 is a perspective view thereof from the bottom; FIG. 11 is an elevational view thereof from the front; FIG. 12 is an elevational view thereof from the rear; FIG. 13 is an elevational view thereof from the left; FIG. 14 is an elevational view thereof from the right; FIG. 15 is a top plan view thereof; FIG. 16 is a bottom plan view thereof; FIG. 17 is a perspective view of a third presently preferred embodiment of the washer of my new design from the top; FIG. 18 is a perspective view thereof from the bottom; FIG. 19 is an elevational view thereof from the front; FIG. 20 is an elevational view thereof from the rear; FIG. 21 is an elevational view thereof from the left; FIG. 22 is an elevational view thereof from the right; FIG. 23 is a top plan view thereof; FIG. 24 is a bottom plan view thereof; FIG. 25 is a perspective view of a fourth presently preferred embodiment of the washer of my new design from the top; FIG. 26 is a perspective view thereof from the bottom; FIG. 27 is an elevational view thereof from the front; FIG. 28 is an elevational view thereof from the rear; FIG. 29 is an elevational view thereof from the left; FIG. 30 is an elevational view thereof from the right; FIG. 31 is a top plan view thereof; FIG. 32 is a bottom plan view thereof; FIG. 33 is a perspective view of a fifth presently preferred embodiment of the washer of my new design from the top; FIG. 34 is a perspective view thereof from the bottom; FIG. 35 is an elevational view thereof from the front; FIG. 36 is an elevational view thereof from the rear; FIG. 37 is an elevational view thereof from the left; FIG. 38 is an elevational view thereof from the right; FIG. 39 is a top plan view thereof; FIG. 40 is a bottom plan view thereof; FIG. 41 is a perspective view of a fifth presently preferred embodiment of the washer of my new design from the top; FIG. 42 is a perspective view thereof from the bottom;

(Continued)

FIG. 43 is an elevational view thereof from the front;
 FIG. 44 is an elevational view thereof from the rear;
 FIG. 45 is an elevational view thereof from the left;
 FIG. 46 is an elevational view thereof from the right;
 FIG. 47 is a top plan view thereof; and,
 FIG. 48 is a bottom plan view thereof;
 The broken lines in all the figures represent portions of the
 washer that form no part of the claimed design.
